UNITED STATES PATENT OFFICE.

ARTHUR R. KRAUSE, OF WOODHAVEN, NEW YORK, ASSIGNOR TO LION ELECTRIC
MANUFACTURING CO., INC., A CORPORATION OF NEW YORK.

DESIGN FOR A HORIZONTAL BRACE BAND FOR LIGHTING-FIXTURE BRACKETS.

Application filed November 23, 1923. Serial No. 7,857. Term of patent 7 years.

To all whom it may concern:

Be it known that I, ARTHUR ROBERT KRAUSE, a citizen of the United States, residing at 3966 Fulton Street, Woodhaven, Long Island, county of Queens, city and State of New York, have invented a new, original, and ornamental design for Horizontal Brace Band for Lighting-Fixture Brackets, of which the following is a specification, reference being had to the accompanying drawing, which forms a part of this application and illustrates my design applied to horizontal brace band for lighting fixture brackets.

In the drawing, Fig. 1 is a front elevation; and

Fig. 2 is a top plan view indicating the position of the band relatively to a wall plate by dot-and-dash lines.

I claim:—

The ornamental design for a horizontal brace band for lighting fixture brackets, as shown.

ARTHUR R. KRAUSE.
